CLAIM

The ornamental design for a razor holder, as shown and described.

DESCRIPTION

FIG. 1 is a perspective view of a razor holder; FIG. 2 is a front elevation view of the razor holder; FIG. 3 is a rear elevation view of the razor holder; FIG. 4 is a left side view of the razor holder; FIG. 5 is a right side view of the razor holder; FIG. 6 is a top side view of the razor holder; FIG. 7 is a bottom side view of the razor holder; and, FIG. 8 is a cross-sectional view of the razor holder along the line 8-8 of FIG. 2.

The broken lines shown are for the purpose of illustrating environmental subject matter and form no part of the claimed design.
